UNITED STATES PATENT OFFICE.

IRVEN H. WILSEY, OF CHICAGO, ILLINOIS, ASSIGNOR TO J. B. TUTHILL, OF CHICAGO, ILLINOIS.

PUMP.

Application filed August 24, 1925. Serial No. 51,917.

The invention relates to improvements in rotary pumps for transmitting oil and other liquids.

An important object of the invention is to

5 provide a new and improved pump which is adjustable to vary the flow of liquid, thereby dispensing with the usual by-pass means employed for this purpose, and saving the power expended in handling the liquid 10 that is ordinarily by-passed.

Another object is to provide a pump of the above character which is adjustable to reverse the direction of flow and to vary the flow in either direction.

15 A further object is to provide a pump which serves to meter the flow of the liquid therethrough, thereby dispensing with the usual orifices required for this purpose.

Another object is to provide a pump of 20 the above character having no valves, such as check valves, thereby requiring power only to pump the oil.

25 A further object resides in the provision of a novel pump which is adjustable so as not to pump any liquid although operating at full speed, thereby permitting starting of the pump under no load conditions.

Another object is to provide a new and 30 improved pump which can be used as an engine.

A further object is to provide a novel 35 pump which is simple and inexpensive in construction, and which is efficient in operation over a wide range, particularly at partial loads since no part of the liquid is bypassed.

Further objects and advantages will be 40 become apparent as the description proceeds.

In the accompanying drawings, Figure 1 45 is a sectional view of a pump embodying the features of my invention taken along line 1—1 of Fig. 2.

Fig. 2 is a sectional view of the pump 50 taken along line 2—2 of Figure 1.

Fig. 3 is a sectional view taken along line 3—3 of Fig. 2.

Fig. 4 is a sectional view of the pump 55 taken along line 4—4 of Fig. 3.

While the invention is susceptible of various 60 modifications and alternative constructions, I have shown in the drawings and will herein describe in detail the preferred embodiment, but it is to be understood that I do not thereby intend to limit the invention 65 to the specific form disclosed but aim

to cover all modifications and alternative constructions falling within the spirit and scope of the invention as expressed in the appended claims.

Referring more particularly to the drawings, the pump comprises a casing 3 which in the present instance is circular in form and which is provided with an annular flange 4. The casing 3 is formed with a central elongated bearing 5 in the outer end of which a packing 6 is held in position by a threaded nut 7. Fitting over the flange 4 and serving to close the casing 3 is a cover 8 which in the present instance is also circular in form and which is secured to the casing by means of a plurality of spaced bolts 9.

Extending through the bearing 5 is a shaft 10 which is adapted to be driven by any suitable source of power (not shown), and which is formed inside the casing 3 with a circular rotor 11. The casing 3 is formed in opposite sides of its inner periphery with opposed recesses separated at the top and bottom by inward projections 12 and 13. These recesses are closed by the rotor 11 to form chambers 14 and 15. The inner surfaces of the projections 12 and 13 are machined, and fit closely against the peripheral surface of the rotor 11. Passages 16 and 17 formed in the top wall of the casing 3 open respectively into the chambers 14 and 15 at opposite sides of the projection 12.

The rotor 11 is formed in its surface next to the cover 8 with a cylindrical recess or chamber 18 concentric with the shaft 10, and with a plurality of equally spaced radial bores 19 opening into said recess and at the outer periphery of the rotor. A plurality of plungers 20 are slidably mounted in the bores 19.

Formed on the outer surface of the cover 8 and positioned eccentrically with respect to the shaft 10 is a bearing 21 having a packing 22 secured in place in its outer end by a gland nut 23. A shaft 24 extends through the bearing 21, and is formed on its inner end with a circular plate or eccentric 25 fitting into a cylindrical recess 26 on the inner surface of the cover 8. A pin 27 is 105 formed on the inner face of the plate 25 eccentrically of the shaft 24, and extends into the recess 18 in which it is adapted to be adjusted in a curved but substantially vertical path by actuating the shaft. The 110

pin 27 carries a bushing 28 on which is mounted a ring 29. The ring 29 is formed with inner and outer spaced annular flanges 30 and 31 respectively, of which the inner 5 flange bears against the inner ends of the plungers 20 and the outer flange fits into lateral notches 32 cut in the sides of the inner ends of the plungers. The inner ends of the plungers and the edges of the slots 10 32 are curved to prevent binding in movement about the ring 29 as the rotor 11 is operated. The ring 29 is substantially smaller in diameter than the recess 18, and can be adjusted substantially in a line 15 between the projections 12 and 13 into positions eccentric thereto by angularly adjusting the eccentric 25.

In operation, when the ring 29 is in its 20 uppermost position, each plunger 20 will be in its outermost position when crossing the projection 12, and in its innermost position when crossing the projection 13. Assuming that the rotor 11 is moving clockwise, as the 25 plungers are moved downwardly, they are gradually drawn inwardly by the flange 31 of the ring 29 because of its eccentric position with respect to the shaft 10. The suction created by the inward movement of the 30 plungers 20 draws liquid through the passage 17 into the chamber 15 and into the outer ends of the bores 19. As each bore is moved over the projection 13, the outer 35 end is cut off from the chamber 15 and the liquid therein is entrapped. As the plungers are moved upwardly on the left side of the 40 casing, as viewed in Fig. 1, the flange 31 gradually forces the plungers outwardly, thereby ejecting the liquid which was entrapped in the bores 19 into the chamber 14 from which it is discharged through the 45 passage 16.

If the shaft 10 is rotated in a counter clockwise direction, the flow through the 50 pump will be reversed, i. e. the liquid will be drawn in through the passage 16 and discharged from the passage 17. If the ring is adjusted into a position below the shaft 10 and the rotor is driven in a clockwise direction, the direction of flow will also be 55 reversed. In practice, the rotor is driven in one direction, and a reversal of flow is obtained by adjusting the eccentric 25 to shift the ring 29 from a position on one side of the shaft 10 into a position on the other side of the shaft. If the ring 29 is 60 positioned in axial alinement with the shaft 10 the plungers will not be actuated and no flow will result, and if the ring is adjusted into different positions intermediate this axial position and either extreme position flows of various sizes in either direction will be obtained.

It will be evident, that the pump can thus be adjusted to produce the desired flow 65 without by-passing any of the liquid there-

from, that the pump therefore serves to meter the liquid, and that since there are no valves the only power required to drive the pump is that required to propel the liquid and to overcome friction. The pump is well balanced, and efficient in operation over a wide range. It can be started under no-load conditions after adjusting the ring 29 into axial alinement with the shaft 10.

I claim as my invention:

1. A pump having, in combination, a hollow casing, a rotor in said casing, said rotor having a central cylindrical chamber and having a plurality of radial bores opening into said chamber, said casing having a pair of diametrically opposed projections bearing against said rotor and dividing the space between said casing and said rotor into chambers at opposite sides of said rotor, inlet and outlet passages communicating with said last mentioned chambers, a plurality of plungers slidably mounted in said bores, each plunger having a lateral notch on its inner end, and adjustable cam means positioned in said first mentioned chamber and engaging in said notches to actuate said plungers upon rotation of said rotor, said cam means being adjustable between said projections relative to the axis of rotation of said rotor to vary the throw of said plungers and thereby vary the flow of liquid through said pump.

2. A pump having, in combination, a hollow casing, a rotor in said casing, said casing having a pair of opposed chambers at opposite sides of said rotor, inlet and outlet passages communicating respectively with said chambers, said rotor having a plurality of radial bores, a plurality of plungers, one mounted in each bore, means engaging said plungers, said means being adapted to be positioned eccentrically of said rotor so as to effect a reciprocation of said plungers upon operation of said rotor, and means for adjusting said last mentioned means to change the eccentricity of the latter relative to the rotor.

3. A pump having, in combination, a hollow casing, a rotor in said casing, said casing having a pair of opposed chambers formed at opposite sides of said rotor and having inlet and outlet passages communicating with said chambers, said rotor having a plurality of radial bores, a plurality of plungers one mounted in each bore, and means engaging the inner ends of said plungers, said means being adjustable into and out of axial alinement with said rotor, and being operative when out of alinement to reciprocate said plungers as said rotor is operated.

4. A pump having, in combination, a hollow casing having inlet and exhaust passages, a rotor in said casing, said rotor having a plurality of bores extending perpendicularly to the axis of rotation and adapted

to be moved into successive communication with said passage, plungers in said bores, cam means mounted in said casing and operatively associated with said plungers, said 5 cam means being adjustable into axial alignment with said rotor, in which position it is ineffectual to actuate said plungers, and into eccentric positions on opposite sides of said last mentioned position to reciprocate said 10 plungers in opposite directions respectively upon rotation of said rotor, the length of reciprocation in either direction being determined by the degree of eccentricity.

5. A pump having, in combination, a hollow casing, inlet and exhaust passages, a 15 rotor in said casing having chambers movable into successive communication with said passages, plungers reciprocable in said chambers, means engaging said plungers and being adapted to reciprocate the latter, said 20 means being adjustable perpendicularly to the axis of rotation of said plungers to adjust the extent of reciprocation and the direction of reciprocation of said plungers relative to said passages.

6. A pump having, in combination, a hollow casing, a rotor in said casing, said rotor

having a central chamber, and having a plurality of radial bores opening from said chamber to the periphery, said casing having a pair of diametrically opposed projections bearing against the periphery of said rotor and dividing said casing into two chambers, inlet and outlet passages communicating respectively with said chambers, 30 a plurality of plungers slidably mounted in said bores, each plunger having a lateral notch on one side of its inner end, the sides of said notches being convex in shape, and each plunger having its inner end rounded, 35 a plate mounted in the inner face of one end wall of the casing for rotary adjustment about an axis eccentric to that of said rotor, a pin extending eccentrically from said plate into said central chamber, and a ring 40 mounted on said pin, said ring being formed with inner and outer spaced concentric annular flanges, said inner flange engaging the inner ends of said plungers and said outer flange fitting into said notches.

In testimony whereof, I have hereunto affixed my signature.

IRVEN H. WILSEY.
